UNITED STATES PATENT OFFICE.

DORA S. DAILY, OF SAN FRANCISCO, CALIFORNIA.

SEPARABLE CUFF OR COLLAR, AND SHIRT.

1,319,851.

Specification of Letters Patent.

Patented Oct. 28, 1919.

Application filed March 17, 1919. Serial No. 283,144.

To all whom it may concern:

Be it known that I, DORA S. DAILY, a citizen of the United States, residing at the city and county of San Francisco and State of California, have invented certain new and useful Improvements in Separable Cuffs or Collars, and Shirts, of which the following is a specification.

My invention relates, in general, to wearing apparel, and particularly to shirts collars and cuffs and their separable assemblage.

The object of my invention is to provide for the separable attachment of cuffs or collars, or both to shirts, by a simple and stable connection which is economical in manufacture and which is easy of operation, at the same time being comfortable and of neat appearance.

To this end my invention consists in the novel assemblage and connection of cuffs or collars, and shirts which I shall now fully describe, by reference to the accompanying drawings in which—

Figure 1 is a perspective view showing the cuff and shirt connection.

Fig. 2 is a section of the same, slightly enlarged, on the line 2—2 of Fig. 1.

Fig. 3 is a perspective view of the collar and shirt connection.

Fig. 4 is a section of the same, on the line 4—4 of Fig. 2.

Referring first to Figs. 1 and 2, the numeral 1 indicates the sleeve of a shirt, the wrist opening of which is secured by the usual button 2. The wrist of the sleeve is formed with or has attached to it the symmetrically oppositely disposed tabs 3. There is one of these tabs on each side, and each can therefore be made relatively wide, as shown in Fig. 1 resulting not only in ease of manipulation, but also in a more stable and firm connection.

4 is the cuff, as of the doubled or folded type.

In the inner fold of the cuff, near its free edge, are made the two slits 5, which have a length adapted for the passage through them of the tabs 3. When the cuff is fitted to the sleeve, and the tabs 3 passed through the slits 5, said tabs are then turned back and are connected with the sleeve by some form of readily detachable fastening. This fastening may be such, for example as I have shown in connection with the collar of Figs. 3 and 4, namely a button and a

button-hole, or it may be as shown in Figs. 1 and 2, a snap assemblage comprising a socket member 6 in the tab, a stud 7 in the sleeve, and an intervening hole 8 in the cuff. In order to provide a good appearance, the position of the slits 5 with respect to the edge of the cuff, and the length of the tabs 3, are such that when the tabs are passed through the slits and fastened back to the sleeve, they and the snap fastening lie wholly concealed under the outer fold of the cuff. Due to the extensive bearing of the relatively wide tabs, the connection is particularly firm and stable, and holds the cuff in true straight position under all circumstances.

It is also apparent that the double cuff may be turned inside out when required to expose a fresh exterior.

In the application of my invention to the folded collar 9, as shown in Figs. 3 and 4, the same construction is preserved, only one tab 3', on the neck portion 1' of the shirt, being here shown, but this tab is as before, relatively wide, and the slit 10 in the collar is adapted in length to receive it. A button 11 on the shirt, and a button hole 12 in the tab, are here shown as a detachable fastening, though a snap fastening may be used. When, as shown in Figs. 3 and 4, a button and button hole are used as a fastening, the button should be placed as near the lower line position of the collar as possible, so that the tab need not project but is concealed between the folds of the collar as seen in Fig. 4.

The separable connection herein described for both cuffs and collars is economical in manufacture, is readily made and broken, is soft and comfortable in wear, and is not unsightly.

I claim:—

1. Separable wearing apparel comprising a shirt having oppositely disposed relatively wide tabs, a folded apparel member adapted to be fitted to the shirt and provided in its inner fold with slits through which the tabs are adapted to be passed and to lie wholly between the folds of said apparel member, and a detachable fastening between the shirt and the passed through ends of the tabs, said fastening lying between the folds of the apparel member.

2. Separable wearing apparel comprising a shirt the sleeve of which has at its wrist portion oppositely disposed symmetrical, rel-

atively wide tabs, one on each side of the wrist opening; a cuff having slits through which the tabs are adapted to respectively pass; and a detachable fastening between the shirt sleeve and the passed through ends of the tabs.

3. Separable wearing apparel comprising a shirt, the sleeve of which has at its wrist portion oppositely disposed symmetrical tabs, one on each side of the wrist opening; a folded cuff having in its inner fold slits through which the tabs are adapted to re-

spectively pass and to lie wholly between the folds of said cuff; and a detachable fastening between the shirt sleeve and the passed through ends of the tabs, said fastening lying between the folds of the cuff. 15

In testimony whereof I have signed my name to this specification in the presence of two subscribing witnesses.

DORA S. DAILY.
